Primary Examiner — Elizabeth J Oswecki(74) *Attorney, Agent, or Firm* — Greenberg Traurig, LLP;
David J. Dykeman; Joshua M. Herman(57) **CLAIM**

The ornamental design for an upright tree skirt, as shown and described.

DESCRIPTION

FIG. 1 is a front view of an upright tree skirt showing my new design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

The broken lines shown in the drawings represent portions of the tree skirt that form no part of the claimed design.
